DEFROST CONTROL APPARATUS FOR A
HEAT PUMP

Wendell E. Maudlin, Lebanon, Ind., assignor to Stewart-Warner Corporation, Chicago, Ill., a corporation of Virginia

Filed May 25, 1961, Ser. No. 112,602
6 Claims. (Cl. 62—156)

This invention relates to a heat pump, and more particularly, to a control arrangement therefor operable to initiate and terminate a defrost cycle automatically upon a build-up and breakdown of frost on the heat pump evaporator coil.

This invention is an improvement in the automatic defrost control shown in Patent No. 2,666,298, issued January 19, 1954, to F. M. Jones.

An object of this invention is to provide a defrost control arrangement having a plurality of temperature sensing means disposed at separate locations in a heat pump operable separately to initiate and terminate a defrost cycle therefor.

Another object of this invention is to provide a refrigerant charged pressure actuated defrost control system having a plurality of interconnected temperature sensing bulbs disposed at spaced locations in a heat pump operable separately to initiate and terminate a defrost cycle therefor.

Another object of this invention is to provide a defrost control arrangement having a closed refrigerant charged pressure system including a bellows and a plurality of interconnected temperature sensing bulbs disposed at the opposite ends of an evaporator coil in a heat pump operable separately to initiate and terminate a defrost cycle for the heat pump responsive to temperature changes therein.

These objects as well as the principle of operation of this invention will be more fully understood and appreciated upon a complete disclosure of a typical embodiment of this invention disclosed in the following specification and drawings forming a part thereof, wherein:

FIG. 1 is a generally schematic heat pump circuit having a defrost control arrangement therefor forming a part of this invention; and

FIG. 2 is a representative temperature vs. time graph of the various temperature sensing elements used in the defrost control forming a part of this invention.

The basic operation of a heat pump is well known by those in the art. A charge of refrigerant, changeable between its liquid and vapor states at the expected heat pump temperatures and commercially operable pressures, is sealed in a closed heat pump circuit. The vaporous refrigerant is compressed in a compressor and directed by appropriate conduits to a condenser coil. Heat transfer between the condenser coil and its ambient fluid withdraws heat from the refrigerant to condense the refrigerant to a high pressure liquid. The liquid refrigerant is conveyed by appropriate conduits to an evaporator coil. Throttling means in the circuit between the coils throttles the pressure of the liquid refrigerant to less than the vapor pressure of the refrigerant at the temperature ambient the evaporator coil. Heat transfer between the evaporator coil and its ambient fluid boils the low pressure liquid refrigerant to a vapor. The vaporous refrigerant is communicated from the evaporator coil to the compressor for recycling in the heat pump.

The heat pump circuit is commonly the same for both the heating and cooling cycles, the main difference being the location of the condenser and evaporator coils with respect to the enclosure to the heat controlled. On a conventional cooling cycle, the outdoor coil acts as the condenser coil whereas the indoor coil acts as the evap-

2

orator coil. On the other hand, for a conventional heating cycle, the indoor coil acts as the condenser coil while the outdoor coil acts as the evaporator coil.

Frost on ice build-up occurs on the evaporator coil when the ambient temperature thereof is approximately 40° or lower. The frost reduces heat transfer of the hot ambient air to the cool refrigerant within the coil to impede complete boiling. Consequently, the overall efficiency of the system is reduced since not all of the refrigerant is boiled and thus used in the heat pump circuit.

FIG. 1 shows a closed heat pump circuit representative of a conventional household air conditioner, and includes a compressor 10 interconnected at its outlet by conduit 12 to a 4-way valve 14. Conduit 16 communicates the 4-way valve 14 to an accumulator 18 and thence to the inlet of compressor 10.

Conduit 20 extends from the 4-way valve 14 to indoor coils 22 or the coils located within the enclosure to be temperature conditioned. A parallel connection extends from coils 22 through check valve 24, and through capillary tubes 26 and strainer and distributor 28, to T 30.

Conduit 32 connects T 30 to T 34. Parallel lines having therein, respectively, conduit 36 and check valve 38, and conduit 40, filter drier 42 and expansion valve 44, in turn interconnect T 34 with T 46. Conduit 48 connects T 46 to one side of outdoor coil 50, or the coil disposed outside of the heat controlled enclosure. Conduit 52 extends from the opposite side of coil 50 and thence back to 4-way valve 14 to complete the heat pump circuit.

Line 54 interconnects expansion valve 44 with the outdoor coil 50 for control of the valve by appropriate temperature or pressure means as is well known in the art. Service valves 56 in conduits 20 and 32 permit easy connection of the lines for installation or servicing. Sight glass 58 in conduit 32 provides visual check of the refrigerant charge in liquid line 32 of the heat pump circuit.

On the cooling cycle the compressed refrigerant is directed from compressor 10 by the 4-way valve 14 through conduit 52 to the outdoor coil 50. The heat transfer between the outdoor coil and the outdoor air condenses the refrigerant to a compressed liquid. The liquid refrigerant is directed by conduit 48 through check valve 38 to T 30. The capillary tubes 26 throttle the refrigerant to a pressure lower than the refrigerant vapor pressure, the refrigerant boiling in indoor coils 22 and absorbing heat from the enclosure. The vaporous refrigerant is directed by conduit 20 to 4-way valve 14 and to the compressor for recycling.

On the heating cycle the compressed refrigerant is directed from compressor 10 via 4-way valve 14 and conduit 20 to the indoor coils 22. Heat transfer with the indoor air condenses the vaporous refrigerant to a liquid. The high pressure liquid refrigerant then flows via check valve 24, conduit 32, through line 40 where the expansion valve 44 throttles the pressure thereof. The low pressure refrigerant is directed by conduit 48 to outdoor coil 50 where it is boiled by the heat of the outdoor air. The vaporous refrigerant is directed by conduit 52 to 4-way valve 14 and thence to the compressor 10 for recycling. When the outdoor air temperature is below 40°, frost will form on the outdoor evaporator coil 50.

Defrosting of the conventional heat pump as shown can be effected by reversing the 4-way valve 14 to direct the hot high pressure refrigerant gas via conduit 52 to the frosted outdoor coil 50. Coil 50 then acts as the condenser coil whereas indoor coil 22 acts as the evaporator coil. In essence such a defrost cycle is identical in operation to the cooling cycle of the heat pump.

This invention utilizes a defrost control similar in part to that disclosed in the above-mentioned Patent No.

2,666,298 to F. M. Jones. The control device 64 includes a lever 66 fulcrumed at pivot point 68 to frame 70. Bellows 72 and 74 are supported by the frame 70 and engage the lever 66 on opposite sides of pivot point 68 so that the bellows oppose each other. A pair of contacts 76 are actuated by rotation of the lever 66 to complete an electrical control circuit including control device terminals 78 and 80. A quick throw mechanism and calibration means are generally included between the lever 66 and contacts 76, but are shown only schematically since they form no part of the present invention.

The electrical control circuit completed by contacts 76 includes appropriate conductors between the control device terminals 78 and 80, outdoor fan 82, control panel 84, and solenoid 86 on 4-way valve 14. The electrical control is such that during the heating cycle, one position of contacts 76 completes control circuits to the outdoor fan 82 and solenoid 86 to power the fan and to hold the 4-way valve 14 in the heating cycle. The other position of the contacts 76, corresponding to a demand for a defrost cycle, completes control circuits to the solenoid 86 and fan 82 to shift 4-way valve to the defrost cycle and to stop the fan. Thus the hot refrigerant gas flow and the reduced heat transfer with the outdoor air readily melts the frost off the outdoor coil 50.

Each of the bellows 72 and 74 forms a separate pressure system charged with a conventional refrigerant, such as Freon 22. The pressure within each system is determined by the temperature of the liquid surface of the refrigerant therein and is the vapor pressure of the refrigerant corresponding to that temperature. Each system has temperature sensing bulb means operable to sense the temperature at particular locations with respect to the heat pump. One sensing bulb means is disposed in the outdoor air ambient in the evaporator outdoor coil 50, while the other sensing bulb means is strapped to the heat pump circuit to sense the temperature of the refrigerant therein.

The difference between the sensed temperatures in the heat pump bellows 74 and the ambient conditions bellows 72 changes the refrigerant pressures therein to actuate contacts 76. By proper proportioning of the bellows 72 and 74 and their location with respect to the lever pivot 68, the necessary change in the difference of sensed temperatures can be readily controlled. Thus reliable temperature responsive means are available with which to actuate an appropriate control to initiate or terminate a defrost cycle.

The improvement forming this invention includes providing a number of separate temperature sensing bulbs connected to the heat pump bellows of the control device 64. The bulbs are placed at separate locations on the heat pump circuit and in a sense act independently of each other to initiate and terminate the defrost cycle.

Conduit 90 connects ambient bellows 72 to temperature sensing bulb 92 which is disposed in the outdoor air ambient the coil 50. Conduit 94 connects heat pump bellows 74 to temperature sensing bulbs 96 and 98. Even though the bulbs 96 and 98 are shown in a series connection with bellows 74, it will be appreciated that the bulbs could also be connected in parallel or separately to the bellows 74, the operation of which would be the same as hereinafter described.

Bulb 96 is strapped or secured to the vapor end of the outdoor evaporator coil 50, as is shown on conduit 52 between the compressor 10 and the coil. Bulb 98 is strapped or secured to the liquid end of the outdoor evaporator coil as on check valve 38 between the coils 22 and 50. Bulb 96 initiates the defrost cycle and has generally no function to terminate the defrost cycle, whereas bulb 98 terminates the defrost cycle and has generally no function to initiate the defrost cycle.

FIG. 2 shows a temperature-time graph of the various temperature sensing bulbs forming a part of the control of this invention. The graph is generally broken up into

the last phases of a heating cycle, a complete defrosting cycle, and the initial phases of a subsequent heating cycle. The temperature of the ambient outdoor air is assumed constant and is shown as sensed by the bulb 92. Similarly, the temperatures of the heat pump as sensed by bulbs 96 and 98 are shown by the curves "bulb 96" and "bulb 98" respectively. The curves are merely representative of a typical heat pump but are not to be limited by their specific values or shapes shown since such could be readily change by conventional means known in the art.

On the heating cycle, as ice builds up on the outdoor coil 50, the reduced heat transfer of the ambient air to the coil decreases the effective boiling of the refrigerant therein. The temperature of the refrigerant leaving coil 50 in vapor conduit 52 thus begins to decrease and is sensed by initiating bulb 96. At the temperature corresponding to the preset actuating pressure difference between the ambient air sensing bellows 72 and the heat pump sensing bellows 74, the control contacts 76 are actuated as hereinbefore outlined. The heat pump cycle is thus switched to a defrost cycle by the control circuit including solenoid 86 of the 4-way valve 14.

Conduit 52 now carries the high pressure hot vaporous refrigerant from compressor 10. Temperature of the vapor line sensing bulb 96 thus rises rapidly to the temperature of the hot refrigerant gas. The refrigerant within bulb 96 vaporizes and migrates toward a cooler location within the system where it then condenses. The temperature of the refrigerant within the outdoor coil 50 is rapidly cooled by the ice formed on the coil. The refrigerant in the heat pump control system thus begins to condense in the bellows 74 and liquid line sensing bulb 98.

The ice on coil 50 rapidly melts because of the large heat quantities given off by the condensing refrigerant therein. The temperature of the refrigerant leaving coil 50 in the liquid line thus begins to rise, and terminating bulb 98 senses such rise. The vapor pressure of the refrigerant within the closed heat pump control system increases until the necessary predetermined pressure difference between the heat pump sensing bellows 74 and the ambient air sensing bellows 72 is reached to actuate the control contacts 76. The control circuit including solenoid 86 returns the 4-way valve 14 to resume the heat pump cycle.

Thus it is seen that the separate temperature sensing bulbs 96 and 98 each control the heat pump control system pressure independently, the bulb having the lower temperature controlling the pressure within the system. This arrangement eliminates defects associated with existing control devices, such as the above-mentioned Jones device, Patent No. 2,666,298, that have only one heat pump temperature sensing bulb generally located intermediate the evaporator coil.

Bulb 96, located on the vapor line from coil 50, initiates the defrost cycle and is not subject to rapid false temperature changes. The vaporous refrigerant from coil 50 is commonly superheated 10 or 12 degrees above the boiling temperature at the vapor pressure in the coil. Since initiating bulb 96 will sense this superheat, control device 64 can be adjusted to respond to a temperature change corresponding to the superheat, thus allowing a greater temperature margin before inducing a defrost cycle. This eliminates most nuisance defrost cycles caused by variations in the heat pump cycle sufficient to vary the temperature within the evaporator coil but which are not caused by frost on the coil. Such variations can be caused by change of tolerance of the expansion valve setting or capillary tubes, slight variations due to the leakage of the refrigerant change, variation in temperature or quantity of the air flowing over the coil, or localized temperature changes due to localized ice formations on the coil.

Immediately following a reversal of the heat pump between the defrost cycle and a subsequent heating cycle, there is no pressure difference across the expansion valve

44. Similarly, the pressure within the outdoor coil 50 is reduced sufficiently to vaporize the liquid refrigerant therein. Since the refrigerant in vapor conduit 52 is already a vapor, there is little temperature change because of reduction of pressure. Thus, the nuisance and sometimes repetitive defrost cycle associated with a single defrost control located intermediate the evaporator coil is eliminated by this multi-bulb arrangement. A rapid drop in temperature of the termination bulb 98 does not reduce the control system pressure sufficiently to initiate the defrost cycle.

It is again noted that the refrigerant condenses within each control system at the location having the lowest temperature, and that the temperature of the liquid refrigerant surface determines the pressure throughout the entire system. Thus the volumes of the bellows 74, conduit 94, and bulbs 96 and 98 must be proportioned such that the liquid surface will be located within the proper bulb to issue the proper defrost control command, regardless if that is the coldest location in the system or not. Pressure throughout the system will be determined then by the liquid surface temperature in the control bulb generally independent of other temperature ambient the system. It has been found that to accomplish the above desired relationship the termination bulb 98 is slightly smaller than the initiating bulb 96.

While a typical embodiment and the preferred bulb locations, have been shown, it is to be understood that various modifications can be made therein without departing from the true spirit of the invention. Thus it is desired the invention be limited not by the arrangement shown, but by the claims hereinafter following.

What is claimed is:

1. In a heat pump defrost control, the combination comprising means for reversing the heat pump from one heat pump cycle to the defrost cycle for the evaporator coil of the one heat pump cycle, a pair of refrigerant charged systems each including a pressure bellows disposed to oppose the movement of the other, the resultant movement of which is operable to actuate the reversing means, one of said systems having a temperature sensing bulb operable to sense the temperature of the air ambient the previously-mentioned evaporator coil, the other of the systems having a pair of temperature sensing bulbs adapted to sense the temperature at the opposite ends of the evaporator coil, one of the bulbs being disposed in temperature sensing relationship with the vapor end of the evaporator coil operable to initiate the defrost cycle, the others of the bulbs being disposed in temperature sensing relationship with the liquid end of the evaporator coil operable to terminate the defrost cycle, said heat pump bellows and bulbs being of such size that the liquid surface of the refrigerant is always located in the cooler of the two bulbs, so that upon a sufficient change in temperature of the heat pump and ambient air, the pressure differences of the systems corresponding thereto actuate the reversing means.

2. A defrost control for a heat pump having two coils acting as operable responsive to temperature changes in one of the coils acting as the evaporator coil during a particular heat pump cycle to initiate and terminate a defrost cycle therefor, the combination comprising, means for changing from the particular heat pump cycle to the defrost cycle, biasing means responsive to the fluid temperature ambient the above-mentioned one coil acting as the evaporator coil, a refrigerant charged system including a pressure bellows opposing the biasing means and a pair of temperature sensing bulbs, one of the bulbs being disposed in temperature sensing relationship with the heat pump on the vapor end of the one coil operable to initiate the defrost cycle, the others of the bulbs being disposed in temperature sensing relationship with the heat pump on the liquid end of the one coil operable to terminate the defrost cycle, said bulbs and bellows being sized appropriately so that the liquid surface of the refrigerant

erant therein is always located in the cooler of the two bulbs, the vapor end bulb being slightly larger than the liquid end bulb.

3. A defrost control device for a heat pump, comprising a frame, a pair of pressure bellows secured to the frame, a movable member operatively connected to the bellows and movable thereby, a temperature sensing bulb connected to one of the bellows and defining a closed refrigerant charged system, said bulb being adapted to sense the temperature ambient the heat pump coil acting as the evaporator coil for a particular heat pump cycle, and first and second temperature sensing bulbs connected to the other of the bellows and defining another closed refrigerant charged system, said last-mentioned bulbs being adapted to sense the temperature of the heat pump itself, the first bulb being disposed in temperature sensing relationship with the heat pump on the vapor side of the previously-mentioned heat pump coil operable to initiate a defrost cycle, and the second bulb being disposed in temperature sensing relationship with the heat pump on the liquid side of the previously-mentioned heat pump coil operable to terminate the defrost cycle.

4. In a heat pump defrost control including a pair of closed refrigerant charged systems each having a pressure bellows and temperature sensing bulb means, said bulb means being operable to sense respectively, the temperatures of fluid ambient the heat pump evaporator coil on a particular heat pump cycle and the heat pump itself proximate the previously-mentioned evaporator coil, so that upon predetermined temperature changes of the heat pump and ambient fluid, the pressure differences of the systems corresponding thereto initiate or terminate appropriately a defrost cycle in the heat pump for the previously-mentioned evaporator coil, the improvement comprising two temperature sensing bulb means connected to the heat pump bellows, one of the bulb means adapted to be disposed in temperature sensing relationship on the vapor side of the previously mentioned evaporator coil operable to initiate the defrost cycle, the others of the bulb means adapted to be disposed in temperature sensing relationship on the liquid side of the previously mentioned evaporator coil operable to terminate the defrost cycle, said heat pump bulb means and bellows being sized so that the liquid surface of the refrigerant is always located in the cooler of the two bulb means, the vapor side bulb being larger than the liquid side bulb.

5. In a heat pump having a circuit including a compressor, a pair of coils, conduits between the compressor and corresponding ends of the coils directing a refrigerant from the compressor to one of the coils acting as the condenser coil for affecting a particular heat pump cycle, and pressure throttling means between the opposite ends of the coil completing the circuit and causing the other of the coils to act as the evaporator coil for the particular heat pump cycle, the improvement being a control for defrosting the above-mentioned other coil automatically upon a buildup of frost thereon, comprising a pressure actuated bellows, first and second bulbs communicating with the bellows and defining a closed refrigerant charged pressure system, said first bulb being disposed in temperature sensing relationship with the vapor end of the other coil operable to initiate a defrost cycle, said second bulb being disposed in temperature sensing relationship with the liquid end of the other coil operable to terminate the defrost cycle, means actuated by the bellows operable to direct refrigerant from the compressor to the corresponding end of the other coil to affect said defrost cycle, and said second bulb being disposed on the heat pump circuit relative to the pressure throttling means so as to be exposed on the defrost cycle to the heat pump refrigerant confined at a pressure substantially the same as that to which first bulb is exposed on the defrost cycle, and to be exposed on the particular heat pump cycle to the refrigerant confined at pressures substantially the same as and different from that to which the first bulb is exposed on the particular heat pump cycle.

6. In a heat pump having a refrigerant charged circuit including a compressor, a pair of coils, a 4-way reversing valve between the compressor and corresponding ends of the coils, pressure throttling means between the opposite ends of the coils, and means operable to reverse the 4-way valve for directing the heat pump refrigerant from the compressor selectively to the vapor ends of the coils and being operable on a particular heat pump cycle to direct the refrigerant to the vapor end of one of the coils then acting as the condenser coil for that heat pump cycle, the improvement comprising a pair of refrigerant charged systems including opposing pressure bellows operable to actuate the reversing means, one of the systems being responsive to the temperature ambient the other of the coils while the other of the systems being responsive to temperature of the heat pump system itself, said second mentioned system including first and second temperature sensing bulbs connected to the heat pump bellows, the first bulb being disposed on the heat pump circuit between the compressor and the other coil effective to initiate the de-

5

10

15

20

frost cycle to actuate the reversing means and cause a reversal of the refrigerant in the heat pump circuit, the second bulb being disposed on the heat pump circuit proximate the opposite end of the other coil exposed to the heat pump refrigerant at generally the same pressure on the defrost cycle as that of the first bulb and exposed to heat pump refrigerant at both substantially the same pressure and a substantially higher pressure on the above-mentioned particular heat pump cycle as that of the first bulb effective to terminate the defrost cycle, and said heat pump bellows and bulbs being of such size that the liquid surface of the refrigerant is always located in the cooler of the two bulbs and the first bulb being slightly larger than the second bulb.
